CLOSURE FOR COLLAPSIBLE CONTAINERS

Samuel Belsey and Patrick Cassin, London,
EnglandApplication May 18, 1932, Serial No. 611,972,
and in Great Britain December 22, 1931

3 Claims. (Cl. 221—60)

This invention relates to a closure for collapsible containers, the closure being of the kind formed by a shutter angularly displaceable across and transversely to the axis of the mouth 5 of the container about a pivot parallel with but eccentric to said axis.

According to the invention, a pivoted closure of the above described kind, is provided with a ramp surface whereby on the shutter being 10 angularly displaced into the closed position over the mouth of the container, the shutter becomes drawn axially towards the mouth of the container.

The ramp surface is provided at the mutually 15 interengaging surfaces of an inturned lug provided on the shutter and of the neck of the container.

In addition to the ramp-lug, the closure shutter preferably has a lug adjacent to the pivot and 20 which by abutting against the neck of the container, limits the angular opening displacement of the shutter. This precludes the shutter from being angularly displaced towards the mouth of the container in a direction other than the 25 direction in which the ramp-lug can engage with a surface provided on the neck of the container for engagement therewith.

A representative example of a collapsible container fitted with a closure shutter as above 30 described, is illustrated on the accompanying drawing, in which:—

Fig. 1 is an elevation showing the shutter closed.

Fig. 2 is a half cross section along the line 35 2—2 of Fig. 1 as viewed towards the mouth of the container.

Fig. 3 is an elevation as viewed at right angles to Fig. 1, and showing the shutter open and the container broken away.

Fig. 4 is a view similar to Fig. 3, but as viewed 40 from a different angle.

Fig. 5 is an end view of the container as viewed from the mouth end and showing the shutter closed.

Fig. 6 is a longitudinal section along the line 45 6—6 of Fig. 5.

a is a collapsible container, the neck *b* of which, formed with the extrusion orifice or mouth *c*, has a lug *d* on one side.

50 *e* is a sheet metal disc which by means of a rivet *f*, passing through a lug *g* on the disc and secured in the above mentioned lug *d* on the neck *b*, is angularly displaceable over the mouth of the orifice *c*.

55 The extremity *g* of the lug *g* is bent out of

the plane of the disc *e* and is directed towards the body *a* of the container, so that by such extremity *g* abutting against the surface of the neck *b*, angular displacement of the disc *e* is limited.

The disc *e* is also provided remote from the rivet *f*, with another lug *h*. This lug *h* is bent out of the plane of the disc *e* and radially inwards, thus providing an inwardly directed claw *h*.

The neck *b* is formed with a second lug *i* located to be engaged by the claw lug *h* on closure of the shutter disc *e*. The surface of the claw *h* is inclined in such direction that on closing the shutter disc *e*, the claw *h* by riding 70 behind the rear surface *i* of the lug *i*, draws the disc *e* tightly against the mouth of the neck *b*.

The rear surface *i* of the lug *i* on the neck *b* preferably is also inclined to match the inclination of the claw *h*.

As can be clearly seen in Fig. 2, when the shutter disc *e* is in the closed position, the radially inwardly directed border of the claw *h* encounters the surface of the neck *b* and thereby prevents displacement of the shutter disc *e* 80 beyond the closed position.

The shutter disc *e* is centrally recessed and a thin cork packing disc *j* is firmly seated in the recess.

I claim:

1. In a closure for a collapsible container having a neck and mouth, a pivot mounted on said mouth parallel with but eccentric to the axis of said mouth, a shutter disc mounted on said pivot outside said mouth and angularly displaceable transversely across said axis, an in-turned claw on said shutter disc and having a border of said claw encountering said neck when said shutter disc is coaxial with said mouth, and a surface on said neck engaged by said claw, 90 said claw and said surface progressively mutually engaging obliquely to said axis.

2. In a closure for a collapsible container having a neck and mouth, a pivot mounted on said mouth parallel with but eccentric to the axis of 100 said mouth, a shutter disc mounted on said pivot outside said mouth and angularly displaceable transversely across said axis, an in-turned claw on said shutter disc having a surface oblique to said axis and having a border 105 of said claw encountering said neck when said shutter disc is coaxial with said mouth, and a surface on said neck progressively engaged by said oblique surface of said claw.

3. In a closure for a collapsible container hav- 110

ing a neck and mouth, a pivot mounted on said mouth parallel with but eccentric to the axis of said mouth, a shutter disc mounted on said pivot outside said mouth and angularly dis-
5 placeable transversely across said axis, an in- turned claw on said shutter disc having a sur- face oblique to said axis and having a border of

said claw encountering said neck when said shutter disc is coaxial with said mouth, and a lug on said neck having a surface progressively engaged by said oblique surface of said claw.
